Picture of a Ford Fairlane retractable hard-top convertible, *The Detroit News*, Apr. 6, 1994.*Primary Examiner*—Melody N. Brown
Attorney, Agent, or Firm—Harness, Dickey & Pierce, P.L.C.[57] **CLAIM**

The ornamental design for a portion of an automotive vehicle having a convertible roof, as shown and described.

DESCRIPTION

FIG. 1 a fragmentary perspective view of a portion of an automotive vehicle having a convertible roof section stowed in a substantially horizontal position with a rear portion of the roof section hidden by a cover; the opposite view of the vehicle is a symmetrically mirrored image of the figure shown; and,

FIG. 2 is a side elevational view of the portion of the automotive vehicle having a convertible roof section stowed in a substantially horizontal position with the rear portion of the roof section hidden by the cover.

The broken lines shown in FIG. 1 are for illustrative purposes only and form no part of the claimed design.

UNITED STATES PATENT AND TRADEMARK OFFICE
CERTIFICATE OF CORRECTION

PATENT NO. : Des. 406,792
DATED : March 16, 1999
INVENTOR(S) : Michael P. Alexander et al

It is certified that error appears in the above-identified patent and that said Letters Patent is hereby corrected as shown below:

On the title page, Item [75],
Under Inventors:, "Michael P. Alexander, Ile;" should be -- Michael P.
Alexander, Grosse Ile; --.

Signed and Sealed this

Thirteenth Day of July, 1999
